UNITED STATES PATENT OFFICE.

WILLIAM C. CODMAN, OF PROVIDENCE, RHODE ISLAND, ASSIGNOR TO GORHAM MANUFACTURING COMPANY, OF PROVIDENCE, RHODE ISLAND, A CORPORATION OF RHODE ISLAND.

DESIGN FOR A TRAY OR SIMILAR ARTICLE.

40,240.

Specification for Design.

Patented Aug. 31, 1909.

Application filed May 14, 1909. Serial No. 496,087. Term of patent 14 years.

To all whom it may concern:

Be it known that I, WILLIAM C. CODMAN, a subject of the King of Great Britain, residing at Providence, in the county of Providence and State of Rhode Island, have invented a new, original, and ornamental Design for a Tray or Similar Article, reference being had to the accompanying drawings.

The figure is a view in perspective showing my design.

I claim—

The ornamental design for a tray or similar article, as shown.

WILLIAM C. CODMAN.
